UNITED STATES PATENT OFFICE

168,195

TABLE LAMP

Morris A. Storchheim, Forest Hills, N. Y., assignor to Mal-Craft Manufacturing Co. Inc., New York, N. Y., a corporation of New York

Application July 12, 1951, Serial No. 15,830

Term of patent 3½ years

(Cl. D48—20)

To all whom it may concern:

Be it known that I, Morris A. Storchheim, a citizen of the United States of America and resident of Forest Hills, in the county of Queens and State of New York, have invented a new, original, and ornamental Design for Table Lamp, of which the following is a specification, reference being had to the accompanying drawing forming part hereof, in which:

Fig. 1 is a side elevation of a table lamp showing my new design.

Fig. 2 is a front elevation of the same.

The dominant features of my design are shown in solid lines in the drawing.

I claim:

The ornamental design for a table lamp, as shown and described.

MORRIS A. STORCHHEIM.
